UNITED STATES PATENT OFFICE

109,358

DESIGN FOR A COSMETIC CONTAINER

R Bernard Ridenour, Mansfield, Ohio, assignor to The Hoff Manufacturing Company, Mansfield, Ohio, a corporation of Ohio

Application November 10, 1937, Serial No. 72,766

Term of patent 3½ years

To all whom it may concern:

Be it known that I, R Bernard Ridenour, a citizen of the United States, residing at Mansfield, in the county of Richland and State of Ohio, have invented a new, original, and ornamental Design for a Cosmetic Container, of which the following is a specification, reference being had to the accompanying drawing, forming a part thereof.

Figure 1 is a side view of a cosmetic container in closed position showing my new design;

I claim:

The ornamental design for a cosmetic container, substantially as shown and described.

R BERNARD RIDENOUR.
